UNITED STATES PATENT OFFICE.

ROBERT CRAWFORD JOHNSON, OF LEICESTER, ENGLAND, ASSIGNOR TO CUBE TEA-POTS LIMITED, OF LEICESTER, ENGLAND.

DESIGN FOR A MILK JUG OR SIMILAR ARTICLE.

Application filed October 26, 1925. Serial No. 15,260. Term of patent 14 years.

To all whom it may concern:

Be it known that I, ROBERT CRAWFORD JOHNSON, a subject of the King of Great Britain, residing at Roxton, Springfield Road, Leicester, England, have invented a new, original, and ornamental Design for a Milk Jug or Similar Article, of which the following is a specification, reference being had to the accompanying drawing, forming part thereof.

The drawing shows a perspective view of a milk jug embodying my new design.

I claim:—

The ornamental design for a milk jug or similar article as shown.

In witness whereof I have signed this specification.

ROBERT CRAWFORD JOHNSON.
